UNITED STATES PATENT OFFICE.

HERBERT HALFPENNY, OF BRANTFORD, ONTARIO, CANADA.

AMUSEMENT DEVICE.

1,393,117.

Specification of Letters Patent.

Patented Oct. 11, 1921.

Application filed February 7, 1921. Serial No. 443,193.

To all whom it may concern:

Be it known that I, HERBERT HALFPENNY, a subject of the King of Great Britain, residing in the city of Brantford, in the county 5 of Brant, Province of Ontario, Dominion of Canada, have invented certain new and useful Improvements in Amusement Devices, of which the following is a specification.

My invention relates to improvements in 10 amusement devices for use in the water and the object of the invention is to devise an apparatus which will provide fascinating sport while in swimming and the use of which will also provide beneficial exercise.

15 My invention consists of a horizontal, flat, main plane adapted to support the body of the operator in the prone position, a propeller suitably mounted under the rear end of the said plane, foot pedals mounted to operate 20 the propeller, a diving head hinged at the front end of the main plane, handles for operating the diving head, twin rudders operated by suitable connection to the diving head operating means, and buoyancy tanks, 25 all as hereinafter more particularly described and illustrated in the accompanying drawings in which—

Figure 1 is a top plan view of my invention, the buoyancy tanks omitted for clear- 30 ness.

Fig. 2 is a bottom plan view thereof, the rear buoyancy tank being omitted.

Fig. 3 is a side elevation with the rear buoyancy tank omitted.

35 Fig. 4 is a rear view showing the method of supporting the propeller and also showing the twin rudders.

Fig. 5 is an enlarged view to show the construction of the bar used in operating the 40 diving head and in steering.

Fig. 6 is a skeleton elevation of the rear end of my device showing the position of the rear buoyancy tank.

Fig. 7 is a rear view and Fig. 8 is a plan 45 view of the tank.

Like characters of reference indicate corresponding parts in the different views.

1 is the main plane which comprises the front portion 2 and the narrowed rear portion 3. 4 is a strengthening keel strip secured longitudinally to the under face of the main plane.

5 is the diving head which extends forwardly from the front end of the main plane

and is hingedly connected thereto by the 55 hinges 6 and a single rod 7 which engages all of the hinges 6.

8 is a transversely disposed bar which is pivoted centrally to the under side of the diving head 5 by the bolt 9, the purpose of 60 which will appear hereinafter.

This bar (see Fig. 5) has the end handles 10 and is provided with the undercut por- 70 tions 11.

14 are quadrants secured to the under face 65 of the diving head and engage respectively the undercut portions 11 for limiting the rotation of the bar 8.

15 are screw eyes carried by the bar 8 for a purpose as will presently appear. 70

16 is a frame carried at the rear of the main plane for supporting the propelling mechanism and rudders.

The frame 16 comprises the two longitudi- 75 nal bent members 17 which are secured to the under side of the portion 3 at 18 and to the upper side thereof at 19.

The propeller 20 is housed in a cage 21 at the rear end of the frame 16 which comprises the guard bars 22 forming part of the 80 frame 16.

The propeller is mounted upon the shaft 23 which has its front end journaled in the hanger 24 secured to the main plane at 25 and its rear end journaled at 26 in the rear 85 cross bar 27 of the frame 16.

28 is a thrust bearing for the rear end of the propeller shaft.

29 is a bevel pinion carried by the front 90 end of the propeller shaft and engages the crown wheel 30 which is fixedly mounted on the transverse shaft 31.

The shaft 31 is journaled in bearings in the side bars 32 of the frame 16 and 33 are thrust collars carried by this shaft. 95

34 are cranked ends formed on the shaft 31 and carry foot pedals 35.

36 are twin, vertical rudders secured to the shafts 37 which have their upper ends pivotally mounted in the under face of the 100 main plane and their lower ends in the cross bar 38 of the frame 16.

39 is a connecting link or distance piece connecting the rudders 36 so that they move together.

40 are steering cables which are secured respectively to the two screw eyes 15 (see Fig. 2) and to the rudders 36. These cables 105

run over the pulley blocks 41 secured to the under face of the main plane.

42 are straps secured to the main plane at 43 for a purpose as will hereinafter appear.

5 44 are air tanks (preferably made of aluminum) which may be detachably secured by the clips 45 to the under side of the wide portion 2 of the main plane (see Figs. 2 and 3).

10 46 is an additional air tank which is carried at the rear end of the device. It is detachably mounted to the rear frame by the hook clips 47 and to the main plane by the clips 48.

15 The construction and operation of my device is as follows:

The main plane is of wood and is shaped so that when placed on the surface of the water it will support the body of the operator comfortably. The upper part of the body rests on the wide portion 2 while the feet engage the pedals 35, the width of the narrow part 3 being such as to allow free and comfortable movement of the legs at 25 each side.

To use the device, it is placed in the water and the operator lies face down thereon. The arms may be passed under the straps 42 so that these straps engage the shoulders 30 and serve to hold the operator in proper position.

The handles 10 of the operating bar 8 are grasped with the hands and it will be evident that when the cranks 34 are rotated 35 that the propeller will be driven through the medium of the crown wheel 30, pinion 29, and shaft 23.

The end thrust of the propeller is taken by the bearing 28 and the side thrust of the 40 crown wheel is taken by the thrust collars 33.

In this way the device will be driven along the surface of the water.

Steering is accomplished by turning the bar 8 about its pivot point 9. The operation 45 of the steering mechanism will be clearly followed from Fig. 2. The rudders 36 being connected by the link 39, both must turn synchronously and will therefore always work in unison. One of the extreme positions of the bar 8 and rudders 36 is indicated in dotted lines in Fig. 2.

By means of the diving head 5 it is possible to submerge.

To do this the head is inclined downwardly by means of the bar 8 into the position shown in dotted lines at A (see Fig. 3). It will now be evident that as the propeller is driven, the forward end of the device will be directed downwardly and thus the complete apparatus will submerge.

To rise again the diving head is moved into the position shown at B (see Fig. 3).

In order to increase the buoyancy of the device, the air tanks 44 may be attached to 65 the forward wide portion 2 which carries

the greater part of the weight of the body of the operator while the tank 46 is carried over the propeller to increase the buoyancy of the rear end of the device and offset the effect of the weight of the propeller, rudders and 70 the mechanism carried at the rear.

These tanks are preferably made of aluminum and are detachably mounted so that they may be removed if desired and the device used without them. They would be 75 made to offer as little resistance to the water as possible and would probably be of pontoon shape as illustrated.

While I have illustrated and described a preferred construction it is to be understood 80 that various modifications could be made in the exact details of construction without departing from the spirit of the invention or the scope of the claims.

For instance other ways of connecting the 85 diving head to the main plane could be used in place of the type of hinge shown, and it might in fact be made rigid with respect to the main plane. In this case the device would only travel along the surface and 90 could not submerge as previously described. Also the details of the rear frame 16 and the cage 21 could obviously be altered.

From the foregoing it will be seen that I have devised an improved amusement 95 device which will provide very fascinating sport.

What I claim as my invention is:

1. An amusement device comprising, a 100 buoyant main plane adapted to support the operator in the prone position, propelling means carried at the rear end thereof and adapted to be operated by the feet of the operator, steering means suitably mounted at the rear end of the device, a diving plane 105 transversely hinged to the front end of the main plane and extending longitudinally forward therefrom, a transversely disposed operating bar pivoted centrally of its length to the diving plane, handles at the ends of said bar, connections between said bar and the steering means at the rear for operating said steering means as the bar is rotated about its pivot point, said bar adapted to incline the diving plane with respect to the 115 main plane when the handles are depressed.

2. An amusement device comprising, a 120 buoyant main plane adapted to support the operator in the prone position, a frame suspended at the rear end thereof, a screw propeller within the frame and mounted upon a longitudinally disposed propeller shaft, a transverse shaft journaled in the frame and in operative engagement with the propeller shaft, cranks carried at the ends of the transverse shaft, said cranks adapted to be rotated by the feet of the operator, a pair of 125 parallel vertically disposed rudders carried within said frame, a distance link connecting said rudders, a diving plane trans- 130

versely hinged to the front end of the main plane and extending forwardly therefrom, a transverse operating bar pivoted centrally of its length to the diving plane, handles at 5 the ends of said bar, steering ropes connecting the rudders to the bar whereby the rudders are turned when the bar is rotated about its pivot point, the diving plane adapted to be swung about its hinge connection by 10 means of the aforesaid handles.

3. An amusement device comprising, a buoyant main plane adapted to support the operator in the prone position, propelling means at the rear end thereof, manually operated steering means, submerging means 15 at the front and loop members engaging the

arms of the operator for retaining the operator in position on the device.

4. An amusement device comprising, a main plane having a wide forward section 20 and a narrower rear section extending longitudinally therefrom, said plane adapted to support the operator in the prone position, propelling means carried at the rear end of the device, a buoyancy tank carried at each 25 side of the wide forward section of the main plane and a further buoyancy tank carried at the rear end of the device.

HERBERT HALFPENNY.
